UNITED STATES PATENT OFFICE.

EDWARD D. STEELE, OF WATERBURY, CONNECTICUT.

BUTTON-SETTING INSTRUMENT.

SPECIFICATION forming part of Letters Patent No. 340,014, dated April 13, 1886.

Application filed February 2, 1886. Serial No. 190,632. (No model.)

To all whom it may concern:

Be it known that I, EDWARD D. STEELE, a citizen of the United States, residing at Waterbury, in the county of New Haven and State of Connecticut, have invented certain new and useful Improvements in Setting-Instruments; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in that class of setting-instruments which are designed for attaching buttons or studs having penetrating-prongs to articles of wearing-apparel, the object of my present improvements 20 being to provide certain novel and simplified means for permitting of the ready insertion of the button or stud into the holding-jaw of the instrument, securing the same rigidly therein until attached to the fabric or material, and 25 permitting of the easy removal of the button or stud, when so attached, from the holding-jaw of said instrument; and to these ends my invention consists, essentially, of the details of construction and general arrangement of parts, 30 all as will be hereinafter fully described, and specifically designated in the claims.

In the accompanying drawings, Figure 1 represents a side elevation of my improved setting-instrument; Fig. 2, a top plan view 35 thereof; Fig. 3, an end elevation; Fig. 4, a detail view, and Figs. 5 and 6 enlarged detail sectional views.

Similar letters of reference occurring on the several figures indicate like parts. 40 In carrying out my invention the setting-instrument is composed of an upper and lower jaw, A B, adapted to be operated by the handles C D, in a manner well known, the upper jaw, A, in the present instance being divided 45 longitudinally at or about the center of the holding mechanism into two parts or sections, a a', the one part or section, a, being formed integral with the lower handle, D, while the other part or section, a', is pivoted to the part 50 a and adapted to close against the side of the same, as fully shown in the drawings.

Through the lower portion of each of the parts or sections a a' is provided an arched opening, b, for the reception of the head of the button or stud, said openings coming into juxtaposition with each other when the pivoted section a' is closed against the stationary part or section a, as fully shown in Fig. 6. The arched openings b are each provided with an inclined or wedge-shaped bottom, c, which taper inwardly toward each other and have their lower inner edges recessed out to receive and hold the head of the metallic fastener or prongs, as fully shown in the detail sectional views. A bifurcated spring, d, or plate of suitable 65 sheet metal, projects through the opening b for the reception of the head and shank of the button or stud, the rear end of said spring or plate being rigidly secured to the outer side of the stationary part or section a by small screws or 70 other suitable means.

The movable part or section a' is pivoted to the rear upper face of the stationary part or section a by means of a suitable screw, e, and is provided with a rearwardly-extending 75 thumb-lever, g, for moving said section a' inwardly or outwardly to or from the stationary section a.

Upon the lower front end of the movable part or section a' is provided a side lug or projection, h, having a slight recess or depression 80 upon its upper face, which is adapted to spring into a recess or cavity, i, of a corresponding shape in the lower front end of the stationary section a, to hold said sections in a locked position until released by the action of the thumb-lever g, or by the pressure applied to attach 85 the button or stud to a fabric or material.

In the operation of attaching buttons or studs having metallic fastening-prongs to fabrics or 90 materials, the movable section a' is thrown outwardly by means of the thumb-lever g, so that the button or stud may be slipped into the forked end of the spring or plate d in the position shown in Fig. 5, one-half of the head of 95 the metallic prongs resting in the recess in the lower end of the wedge-shaped bottom. The movable section a' is then swung into position against the stationary section a, the wedge-shaped bottom of the same projecting beneath 100 the forked end of the spring or plate d, serving to draw the metallic fastener up into a rigid

position in the recesses in the lower inner ends of the inclined bottoms, as fully shown in Fig. 6. The handles C D of the instrument, being now compressed together, force the fastening-prongs through the fabric or material, and, by means of suitable dies in the lower jaw, B, clinch the same upon the lower surface thereof to hold the button or stud securely in place. When so attached, the button or stud is released from the holding mechanism by swinging back the movable section a' and slipping the same off the forked end of the spring or plate d.

By means of my improvements the operation of attaching buttons or studs to fabrics is greatly facilitated, insuring of the ready introduction of the button or stud in the holding mechanism in the simplest and best possible manner, as also permitting of the easy withdrawal of said button or stud from the holding mechanism when attached in the desired position upon a fabric or material.

Having thus described my invention, I claim as new and useful—

1. As an improved article of manufacture, the herein-described setting-instrument composed of the jaws A B and handles C D, the upper jaw, A, of which is divided into a sta-

tionary section, a, and movable section a', each of which is provided with arched openings b, 30 and wedge-shaped bottoms having recesses to receive and hold the head of a metallic fastener, said stationary section a being provided with a forked spring, d, and end recess, i, and the movable section a' being pivoted to the 35 section a and provided with thumb-lever g, and side projection, h, and the lower jaw, B, of the instrument being provided with dies k, substantially as and for the purpose specified.

2. In a setting-instrument, the upper jaw, 40 A, composed of the stationary section a, formed integral with the handle D and provided with the opening b, forked spring d, end recess, i, and wedge-shaped bottom, in combination with the movable section a', pivoted to the rear part 45 of the stationary section a and provided with thumb-lever g, arched opening b, and side projection, h, substantially in the manner shown, and for the purpose described.

In testimony whereof I affix my signature 50 in presence of two witnesses.

EDWARD D. STEELE.
